UNITED STATES PATENT OFFICE.

TAKEJIRO, YAMAMOTO, OF TOKYO, JAPAN.

INTERTWISTED NET.

1,390,325.

Specification of Letters Patent. Patented Sept. 13, 1921.

Application filed May 29, 1919. Serial No. 300,569.

To all whom it may concern:

Be it known that I, TAKEJIRO YAMAMOTO, subject of the Emperor of Japan, residing at No. 161 Honmuraicho, Azabu, Tokyo, Japan, have invented certain new and useful Improvements in Intertwisted Net, of which the following is a specification.

This invention relates to improvements in intertwined netting.

10 An object of the invention is to provide a strong netting made from cord or rope without employing knots which weaken the net and shorten its life.

Another object of the invention is to improve upon the construction disclosed in my prior Patent No. 1,026,544, dated May 14, 1912.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claim.

30 In the drawing,

Figure 1 shows a pair of cords or ropes after being intertwined with the strands shown separated.

Fig. 2 is a view showing the joint after the two intersecting cords have been twisted tightly together.

The material of the netting of the present invention is made from cord or rope having three strands. There may be many methods of intersecting the strands of the ropes, but the figures of the drawing illustrate the most desirable method.

The two intersecting cords shown in the drawing each comprise three strands, one cord including strands numbered 1, 2 and 3, and the other cord comprising the strands numbered 4, 5 and 6. Before the cords are twisted, they are interlocked in the manner shown in Fig. 1, where each strand of each cord is shown as passing between two of the three pairs of strands of the other cord.

Thus strand 4 is passed between strands 1 and 2 and also between strands 1 and 3, but is not passed between strands 1 and 2. Strand 3 of the other cord is passed between strands 5 and 6, and between strands 4 and 5, but not between strands 4 and 6. Similar statements may be made of all the six strands of the intersecting cords.

When once the strands have been connected in the manner illustrated in Fig. 1, the intersecting cords will be twisted, the twisting taking place simultaneously so that the joint is ultimately intertwined tightly to form the compact knotless joint illustrated in Fig. 2. The joint of the invention, unlike a knotted joint, has no greater thickness than the thickness of the individual cords intersecting to form the joint. The three intertwined strands of the intersecting cords positively prevent any shifting of the two cords relatively to each other.

In the construction of the prior patent referred to, the joint is not solid enough and will loosen after a short time. Especially is it not suitable for a large cord. The present invention has been devised to eliminate the disadvantages of the prior construction. Here the joint is very solid and is suitable for large cords or ropes. The meshes of the netting are of uniform strength and may not be deformed. Even when the netting is nearly worn out the meshes will maintain their proper size, thus making the netting a very durable one.

What is claimed is:—

An interlocked netting joint formed from two intersecting cords or ropes, each cord comprising three strands, each strand of either cord being passed between two of the three pairs of strands of the other cord, no two strands of either cord passing between the same strands in the same direction, the two cords being subsequently twisted tightly to form a knotless joint.

In testimony whereof I have hereunto set my hand in presence of two subscribing witnesses.

TAKEJIRO YAMAMOTO. [L. s.]
